FIG. 2.

UNITED STATES PATENT OFFICE.

FRANK MARTINELLI AND EDWIN ACKER, OF NEW YORK, N. Y.

PERSPECTIVE-DRAWING DEVICE.

Application filed April 18, 1928. Serial No. 270,838.

This invention relates generally to drawing devices, and has more particular reference to a novel perspective drawing device.

The invention has for an object the provision of a device of the class mentioned, which is of simple durable construction, desirable and efficient in operation, and which can be manufactured and sold at a reasonable cost.

10 The device proposes the use of a base member provided with means for attachment on a drawing board and arranged for directing a T-square over the board and towards a vanishing point or points off of the board. The base is formed with grooves which are the arcs of circles described from points along a common line, and preferably these grooves should be numbered for indicating the lengths of the radii or diameters of the circles. A flexible flat member has its lower edge arranged for engaging in any one of the grooves for assuming the shape of the particular groove. This member projects above the base and serves to guide the 25 T-square.

Any arrangement may be made for adapting the T-square to be guided by the said flexible member. Since two points on the arc of a circle determine radial lines of the circle, 30 the T-square may be provided with two rollers arranged for engagement with the flexible member for correctly positioning the T-square.

In the making of perspective drawings, all 35 horizontal lines on each plane of any subject converge to a common center, technically known as a vanishing point. It often occurs that said vanishing points are established at various distances off the drawing board, in 40 such instances it is necessary to employ the use of "perspective curves" which are arcs, (usually of wood) cut to the desired radius. These curves are tacked upon the drawing board and used with a perspective T-square 45 whose end placed against the perspective curve forms a chord. This chord or T-square head has its contact points equidistant from the drawing edge of the blade of the T-square. This drawing edge being a perpendicular and 50 bisecting line of the arc, or ends of the T-square, produced will intersect the center of the circle of which the perspective curve is an arc. Obviously the moving of the T-square head against the perspective curve 55 will maintain its intersecting relationship to

the center of the circle of which the perspective curve is an arc. This center is technically known as a perspective vanishing point and as the vanishing point conditions are numerous an architect now requires a great 60 number of perspective curves of various radii.

Our invention eliminates a multitude of perspective curves by combining any number of arcs or perspective curves of varying radii in one unit as shown and described. 65

For further comprehension of the invention, and of the objects and advantages thereof, reference will be had to the following description and accompanying drawings, and to the appended claims in which the various 70 novel features of the invention are more particularly set forth.

In the accompanying drawing, forming a material part of this disclosure:

Fig. 1 is a perspective view of a drawing 75 board provided with the said device.

Fig. 2 is an enlarged face view of the device itself.

Fig. 3 is a fragmentary enlarged vertical sectional view, taken on the line 3—3 of Fig. 2. 80

Fig. 4 is a similar view of a modified form of the device.

Fig. 5 is an enlarged sectional view, taken on the line 5—5 of Fig. 2.

Fig. 6 is a fragmentary sectional view of 85 the device and the drawing board and showing the T-square applied thereto.

Fig. 7 is a fragmentary perspective view of an ordinary T-square showing the bottom side thereof facing upwards. 90

The reference numeral 10 indicates generally a drawing board, and 11 a T-square therefor. The particular type of drawing board and T-square forms no limitation in this invention. 95

A base member 12 preferably of rectangular shape is formed with corner cavities 13 in which tacks 14 are movably mounted. Apertures 15 are formed in the base and the pointed members 16 of the tacks may be manually 100 pressed thru these apertures for securing the base upon the drawing board. The tacks are formed with raised edges 17 for engagement by a person's finger nail for loosening the tacks from the drawing board. 105

A plurality of grooves 18 are formed in the top surface of the base member 12. These grooves are arc shaped, reference being had to a plan view thereof, and are arcs of circles described from points along a common line. 110

Numbers are provided adjacent each groove for stating the length of the radii of the circles from which the arcs are described, and these numbers are indicated by numeral 19 on the drawing. These grooves extend completely to the edges of the base member.

Fig. 3 shows these grooves of dove tailed construction, considered transversely, while Fig. 4 shows modified grooves 18' of bulbed form.

A flexible member 20 is constructed to slidably engage in the grooves 18 at its top or bottom edges. Obviously this flexible member assumes the curvature of the particular groove in which it is placed. A flexible member 20' is shown engaged in the grooves 18'.

The T-square shown in Fig. 1 is the usual perspective T-square in which the working edge 11' is equidistant from the two edges 11^a of the head of the T-square.

The T-square 11^b shown in Figs. 6 and 7 has a pair of vertically arranged rollers or pins 21 on its top side of the head thereof. These rollers are equally spaced from the drawing edge of the T-square. As shown in Fig. 6 the rollers or pins 21 with T-square, top side down may be engaged against the flexible member 20, and then the drawing edge of the T-square is directed to the center of the circle of the particular groove 18 in which the flexible member is engaged, or in other words toward a point which may be used for a vanishing point. The dot dash lines 22 in Fig. 1 show the T-square in this position. The T-square may be moved along the flexible member, but will always be directed to the same point.

In Fig. 1 the dot dash lines 23 indicate several of the devices placed together and aligned with their similar grooves so as to be usable as one device. Thus it is seen that the device may be of small sections.

While we have shown and described the preferred embodiment of our invention, it is to be understood that we do not limit ourselves to the precise construction herein disclosed and the right is reserved to all changes and modifications coming within the scope of the invention as defined in the appended claims.

Having thus described our invention what we claim as new and desire to secure by United States Letters Patent is:

1. In combination with a drawing board and a T-square, a base secured to the drawing board, and formed with arc-shaped grooves representing the arcs of circles described from different points on a common line, a flexible member adapted to engage in any one of the grooves for assuming its shape, and a pair of abutments on the head of the T-square engageable against the flexible member and arranged for directing the T-square towards the center of the circle from which the arc is described.

2. In a drawing device, a base securable to a drawing board, and formed with arc-shaped grooves representing the arcs of circles, different radii scribed from different points on a common line, and a flexible member engageable in any of the grooves for assuming its shape for the purpose described.

3. In combination with a drawing board and a T-square, a base secured to the drawing board, and formed with arc-shaped grooves representing the arcs of circles of different radii, a flexible member adapted to engage in any one of the grooves for assuming its shape, and a pair of abutments on the head of the T-square engageable against the flexible member and arranged for directing the T-square towards the center of the circle from which the arc is described.

4. In combination with a drawing board and a T-square, a base secured to the drawing board, and formed with arc-shaped grooves extending completely to the edges and representing the arcs of circles described from different points on a common line, a flexible member adapted to engage in any one of the grooves for assuming its shape by reason of being slid in thru one end, and a pair of abutments on the head of the T-square engageable against the flexible member and arranged for directing the T-square towards the center of the circle from which the arc is described.

In testimony whereof we have affixed our signatures.

FRANK MARTINELLI.
EDWIN ACKER.
